UNITED STATES PATENT OFFICE.

SVEN JULIUS STRID, OF CHICAGO, ILLINOIS, ASSIGNOR TO FRED MATHEWS, OF CHICAGO, ILLINOIS.

DOUBLE-END CONTROL.

Application filed January 21, 1926. Serial No. 82,794.

My present invention relates to a mechanism for controlling the transmission and associated devices that are used in a motor driven railway car, and it has more specific reference to a mechanism that may be operated from either end of the car and is capable of being readily shifted by a master device that will position the parts so that the motor-man will be able to operate the car from either end.

In motor driven railway cars of certain types there is provided a gas engine or other motor at or on one of the trucks or within the car, and the motor-man in a cab at an end of the car regulates the application of power through the medium of a suitable transmission whereby it is possible to drive the car in a forward or reverse direction and at different speeds in the manner of an automobile. It is frequently necessary, in the ordinary course of running the car for the motor-man to leave what may be called the front end and go to the other or rear end of the car to drive it and with this in view I have designed a control that may be operated from either end of the car simply by throwing a lever or pedal which operates a shifting device or master mechanism so that one of the control operating mechanisms is rendered inoperative while the other is moved into operative position.

It is an object of my invention to provide a control mechanism of the character suggested that is simple and dependable in operation, that is novel in construction, and which is assembled from few parts so that the expense of installing my device is moderate as compared with other types.

I prefer to carry out my invention and to accomplish the diverse objects thereof in substantially the manner hereinafter fully described and as more particularly pointed out in the claims, reference being here made to the accompanying drawings that form a part of this specification.

In the drawings:—

Figure 1 is an underneath view of a railway car that is fore-shortened as its relative length and showing my invention installed thereon in plan.

Figure 2 is a plan of the control mechanism drawn to a larger scale and detached from the car.

Figure 3 is a side elevation of the structure illustrated in Figure 2.

Figure 4 is a transverse section on line 4—4 of Figure 2, and drawn to a larger scale.

Figure 5 is a longitudinal section on line 5—5 of Figure 4 and illustrating the shifting mechanism of the master device.

Figure 6 is a longitudinal section on line 6—6 of Figure 4 and illustrating one of the control units in longitudinal section.

Figure 7 is a side elevation of the clutch shift lever and the foot pedals that operate the controls. Figure 8 is an elevation of the structure shown in Figure 7 looking at the same from the right-hand side.

The drawings are, in a sense, merely schematic for the purpose of illustrating a typical or preferred embodiment of the principles of my invention, and in these drawings I have employed similar reference characters to designate the same parts wherever they appear throughout the several views.

Referring first to Figures 3 and 5 of the drawings, it is seen there is a pair of spaced supports 10 upon the truck frame 11 of the railway car, which supports are angle means and each supports an irregular stationary frame on which frames the major portion of the control mechanism is mounted.

Each frame consists of spaced parallel side pieces, the central portion 12 being straight above the supports 10 by oblique arms 13 arising from adjacent ends of the flat attaching portions 14, while the outer ends of these attaching portions are provided with arms 15 that are slightly oblique to the vertical plane and are connected at their upper ends with cross pieces 20 that extend from one frame to the other and in the ends of which are bearings 16. The bores of these bearings in corresponding ends of the cross-pieces are in alignment with each other as shown in Figure 5 for the purpose of permitting the ends of the spaced parallel slide rods 17 to move thereon. These rods form the side pieces of a reciprocable or vibratory frame that is completed by connecting the slide rods by transverse cross pieces 18 that are positioned parallel with each other and are bored adjacent their ends so that the rods may be positioned to the same and said cross pieces are adjustably secured in position by transverse set screws 19 that may be tightened against the rods.

Bolted to the horizontal central portion 12 of each main side frame is an inverted substantially V-shape bracket 21 the apex of 110

each of which is bored transversely to provide alining bearings 22 for a horizontally disposed rock-shaft 23, which shaft extends through its bearings at one end and provided with a bevelled pinion 24. Crank arms 25 are secured to rock shaft 23 above the respective slide rods 17 which arms are provided at their outer ends with bifurcations 26 between which are positioned the 10 ears 28^a of suitable collars 28 that are adjustably secured to the slide rods 17 intermediate the cross pieces 18 and the arms of the bifurcation are provided with slots 27 that engage the shanks of the bolts 27^a that 15 clamp the ears 28^a together and secure the collars on the rods. Thus when the rock shaft 23 is actuated the vibratory slide frame will be moved by the crank arms longitudinally in one direction or the other in 20 the bearings 16. The means for actuating rock-shaft 23 comprises a stub shaft 29 rotatable in a bearing 30 on the side of one of the V-shaped brackets 21, which shaft is at right angle to rock shaft 23 and has a bevelled gear 31 upon one end that is in mesh with the bevelled gears 24 on the adjacent end of the rock shaft 23, while the opposite end of said stub shaft 29 has a universal connection 32 with the tubular member 33 of an 25 extensible or telescopic shaft, the other member 34 of which shaft enters the tubular member 33 and is feathered therein so that the two portions 33 and 34 rotate together. The shaft 33—34 is one of the elements 30 which for convenience is here termed the "master control" because of the fact that the operation of this portion of the structure shifts the sliding frame from one of its positions to the other so that the engine or 35 motor and the transmission controls may be operated at the one or the other end of the car.

The master control shaft 33—34 extends from the transverse center of the car, where 40 the hereinbefore described structure is located, towards the longitudinal side of the car where its end has universal connection 35 with a short crank shaft 36 having its ends journaled in opposite side members of 45 a rectangular shape frame 37 supported in any suitable manner upon the bottom of the car. A crank arm 38 is secured to the crank shaft 36 intermediate the bearings of the latter and a rod 39 of the like is pivotally connected to the free or outer end of the crank arm and extends therefrom to the front end of the car where it is provided with any suitable means such as a lever *a* that is accessible within the motor-man's cab for moving 50 the rod longitudinally, which lever may be maintained in forward or reverse position on a ratchet segment *b*. When the motor-man desires to change his position from the cab at the front end to the cab at the rear 55 end of the car and operate the motor and

clutches from the rear position he need only shift the lever *a* to its opposite position which will rotate the master control shaft 33—34 and rock the shaft 23 so that the sliding frame is moved to its other position and render the rear control elements operative as will hereinafter be pointed out. 70

Intermediately disposed cross bars 40 connect the side frames and are provided with transverse apertures that afford bearings 75 for opposite portions of a plurality of bell-crank shafts 41, 42, 43, and 44, that may be rotated therein but which are prevented from longitudinal movement by collars 45 secured to said shafts by set screws 46. 80 These stationary cross pieces 20 are bored transversely to provide bearings for two sets of connectors or coupling shafts 47, corresponding in number in each set to the respective bell-crank shafts 41, 42, 43 and 44 and 85 each alining pair of connector shafts (one from each set) is in axial alinement with the respective bell-crank shaft co-acting with that pair. The ends of these connector shafts project upon opposite sides of the 90 stationary crosspieces and are each provided with an annular groove 48 so that when lockpins 49 are inserted in the cross pieces 20 tangent to the shafts 47 said pins will engage said grooves and maintain the shafts 95 against longitudinal movement but permit these connector shafts to be rotated. Two sets of sleeves 50 are rotatably mounted in transverse bores made in the two cross pieces 18 of the sliding frame (one set of sleeves in 100 each cross piece) and the interiors of said sleeves are provided with longitudinal ribs 51 that engage longitudinal grooves 52 in the connector shafts 47 and corresponding grooves 53 in the adjacent end of the bell-crank shafts 41 to 44, so that there is a 105 feathered connection made between each of the bell-crank shafts and the sleeves and between one set of sleeves and the adjacent set of connector or controller shafts. When the 110 grooves in shafts 47 are alined with the grooves in shafts 41 to 44 the master control structure may be operated to shift the sliding frame from one set of shafts 47 to the other set of shafts at the opposite end of the 115 frame.

A universal joint 54 is secured to the outer end of each of the connector shafts 47 and extending from these universal joints are telescopic shafts 55, 56, 57 and 58, each of 120 which is constructed similar to the master control shaft 33—34 hereinbefore described and at their outer ends these telescopic shafts are provided with universal joints 59, 60, 61, and 62 respectively that operatively 125 connect the same with the short shafts 63, 64, 65 and 66 that are disposed parallel with each other. The short shafts 63 to 66 at one end of the mechanism are mounted in bearings 130 in the rectangular frame 37 in which

is also mounted the short rock shaft 36 of the master control shaft 33-34, while the shafts 63, to 66 at the opposite end of the mechanism are mounted in a rectangular frame 37^a supported in any suitable manner upon the bottom of the car. As seen in Figure 3, the frames 37, 37^a are in a different plane than that of the main frame which is on the truck so that the universal joints 10 above mentioned are provided and the telescopic shafts are inclined with respect to the other shafts. Downwardly extending crank arms 64^a, 65^a and 66^a are secured to the respective shafts 64, 65, and 66 that are 15 mounted in frame 37^a and in upwardly extending crank arm 63^a is secured to the shaft 63. In the frame 37 the crank arms 63^a, 64^a 20 65^a and 66^a all extend upwardly from their respective shafts 63 to 66. Elongated rods 63^b, 64^b, 65^b and 66^b are connected with the respective arms of the short shafts 63 to 66 in the frame 37^a and extend therefrom to the far end or rear of the car where they have suitable connection with foot pedals 25 or levers *w*, *x*, *y*, and *z* to be operated by the motor-man within the cab at the rear end of a car, while similar rods 63^b, 64^b, 65^b and 66^b are pivotally connected with the ends of the arms on the short shafts in the frame 30 37 and extend to the foot pedals *w*, *x*, *y* and *z* in the cab at the front end of the car. The foot pedals and connections with the operating rods are of well-known and standard construction and require no detail description.

35 In the structure I have herein illustrated each bell-crank shaft 41, 42, 43 and 44 and the respective telescopic shafts, short shafts and rods, are for operating certain definite parts of the transmission through the medium of crank arms 41^a, 42^a, 43^a and 44^a 40 respectively that are secured to the respective bell-crank shafts 41, 42, 43 and 44. For example the bell-crank shaft 41 through either of its sleeves 51 the short shaft 47, the telescopic shaft 55, the rock shaft 63 and the rod 63^a is connected within the cab at each end of the car with the "reverse" 45 foot pedal *w*; the bell-crank shaft 42 through its respective connections is operatively connected to and actuated by the speed pedal *x* for first and second speeds; the bell-crank shaft 43 is connected and actuated by the speed pedal *y* for the third and fourth speeds 50 and the bell-crank 44 is connected and actuated by the clutch pedal *z*. For convenience in reading the drawings the respective telescopic shafts have been labeled in the manner above described at the left hand of 55 Figure 2. The respective bell-crank shafts 41 and 44 have secured to them the crank arms 41^a to 44^a respectively as has heretofore been described and said arms have pivotal connections with the rods 41^b, 42^b, 43^b

and 44^b that extend respectively to the reversing mechanism of the transmission, the first and second speed mechanism of the transmission, the third and fourth speed mechanism of the transmission, and the clutch mechanism of the transmission.

65 When it is desired to shift the control from one end to the other of the car as from the front to the rear the motor-man throws the lever *a*, which is in the front cab only, to operate the rod 39 so that through the short shaft 36 the master control shaft 33-34 is rotated causing a rocking of shaft 23 through the gears 31 and 34. This rocking of shaft 23 moves the slide frame from one position to another and causes the tubes 70 51, which have been connected with one end of the bell-crank shafts, to be disconnected therefrom, while the other tubes 51 moves over and engages the opposite end of the bell-crank shafts thus forming an operative 75 connection with the telescopic shafts 55, 56, 57, and 58 that are connected with the mechanism and pedals at the opposite end of the car. It will be understood, that prior to the making of this shift the splines and feathers of the shafts and tubes must all be 80 in alignment or in "neutral" position so that when the tubes at one end of the sliding frame are withdrawn from the bell-crank shafts the tubes at the opposite end of the 85 sliding frame will readily come into engagement or coaction with the opposite ends of the respective bell-crank shafts. In the drawings the bell-crank shafts 41 to 44 are 90 illustrated in all of the views as being set 100 so as to be operated by the motor-man in the cab at the front end of the car which is the left end in Figure 1 and are disconnected from the control pedals at the opposite or rear end of the car and the sliding frame is positioned to the left in Figures 5 and 6 for the purpose of disconnecting the left hand set of sleeves 50 from the bell-crank shafts.

105 95 105 110 What I claim is:

1. A control mechanism of the kind described comprising a plurality of bell-crank shafts, a stationary frame in which said shafts are mounted, a set of transmission elements extending from each end of said bell-crank shafts, connector devices interposed between the respective ends of the bell-crank shafts and transmission elements, and means for rendering one set of connector devices operative with respect to the bell-crank shafts and one set of transmission elements, and for rendering the other set of connector devices inoperative.

115 120 125 125 2. A control mechanism of the kind described comprising a plurality of bell-crank shafts, a stationary frame in which said shafts are mounted, a set of transmission elements extending from each end of said

bell-crank shafts, a sliding frame movable with respect to said bell-crank shafts, connector devices carried by said sliding frame and interposed between the ends of said bell-crank shafts and said transmission elements, and means for moving said sliding frame whereby to render one set of connector devices operative with respect to the bell-crank shafts and one set of transmission elements and simultaneously rendering the other set of connector devices inoperative.

3. A control mechanism of the kind described comprising a plurality of bell-crank shafts, a stationary frame in which said shafts are mounted, a set of telescopic transmission shafts extending from each end of said bell-crank shafts, universal joints at the end of said transmission shafts nearest said bell-crank shafts, two sets of connector devices interposed between the ends of said bell-crank shafts and the respective universal joints and operatively connected to the latter, and means for moving one set of connector devices into operative connection with said bell-crank shafts and disconnecting the other set therefrom.

4. A control mechanism of the kind described comprising a plurality of bell-crank shafts, a frame in which said shafts are mounted, a plurality of transmission elements extending from adjacent opposite ends of said bell-crank shafts, a corresponding plurality of connector devices interposed between said bell-crank shafts and said transmission elements, a frame in which said connector devices are mounted, and means for causing a relative movement between said frames whereby operative connection is made between said bell-crank shafts and an adjacent set of transmission devices.

5. A control mechanism of the kind described comprising a plurality of bell-crank shafts, a frame in which said shafts are mounted, oppositely disposed sets of transmission shafts terminating adjacent opposite ends of said bell-crank shafts, sleeves, movable with said transmission shafts and slidable on the ends thereof adjacent said bell-crank shafts in alinement with the latter, and means for causing a relative movement between said bell-crank shafts and said sleeves whereby the latter are engaged alternately with opposite ends of the latter.

6. A control mechanism of the kind described comprising a plurality of bell-crank shafts, a frame in which said shafts are mounted, oppositely disposed sets of transmission shafts terminating adjacent opposite ends of said bell-crank shafts, sleeves movable with said transmission shafts and slidable on the ends thereof adjacent said bell-crank shafts in alinement with the latter, a reciprocable frame in which said sleeves are mounted, means for moving said reciprocable frame whereby said sleeves al-

ternately engage opposite ends of said bell-crank shafts.

7. A control mechanism of the kind described comprising a plurality of bell-crank shafts, a frame in which said shafts are mounted, oppositely disposed sets of transmission shafts terminating adjacent opposite ends of said bell-crank shafts, sleeves movable with said transmission shafts and slidable on the ends thereof adjacent said bell-crank shafts in alinement with the latter, a reciprocable frame in which said sleeves are mounted, a rock shaft, an arm projecting from said rock-shaft and operatively connected with said reciprocable frame and means for actuating said rock-shaft whereby to cause one set of said sleeves to engage with the ends of the bell-crank shafts positioned in one plane and then the remaining sleeve to engage with the opposite ends of said bell-crank shafts.

8. A control mechanism of the kind described comprising two sets of transmission shafts extending in longitudinal planes and the sets spaced end to end with respect to each other, bell-crank shafts interposed between the spaced ends of said transmission shafts, all of the said shafts capable of rotative movement only, axially sliding and rotatable sleeves interposed between the ends of said bell-crank shafts and said transmission shafts, a slide frame having transverse members in which said sleeves are rotatably mounted, a transverse rock-shaft, and means operatively connecting said rock-shaft and frame whereby the latter is moved from one position to another to simultaneously connect and disconnect the respective sets of transmission shafts through said sleeves with the respective adjacent ends of said bell-crank shafts.

9. In a device of the character described, two sets of oppositely extending transmission elements adjacent ends of which are separated from each other, a plurality of shafts arranged for connection with the respective sets of elements, a plurality of devices for connecting one set of elements to said shafts and disconnecting the other set of elements from said shafts, and means for shifting said connecting devices.

10. In a device of the character described, two sets of oppositely extending transmission elements adjacent ends of the respective elements terminating in fixed parallel spaced planes, a plurality of shafts interposed between the spaced ends of said transmission elements, and means alternately connecting the respective ends of said shafts with an adjacent set of transmission elements.

Signed at Chicago, in the county of Cook, and State of Illinois, this 15th day of December, 1925.

SVEN JULIUS STRID.
